WHISTLE

Application filed October 3, 1930. Serial No. 486,113.

This invention relates to operating mechanism for locomotive whistles of the type adapted to be operated either manually or by fluid pressure.

The object of the invention is to provide an improved fluid actuated mechanism for operating the whistle, which can be used with a whistle of the usual manually operated type, and which, while being simple and highly efficient in operation will be of durable and economical construction, embodying a minimum number of parts.

In the accompanying drawings illustrating a specific embodiment of the invention, Figure 1, is a partial side view of a locomotive with the invention applied thereto; Fig. 2, is a vertical section of a whistle having part of the actuating mechanism applied thereto; Fig. 3, is a horizontal section on the line III—III of Fig. 2; Fig. 4, is a side elevation of the whistle valve; Fig. 5, is a horizontal section on the line V—V of Fig. 4; and, Fig. 6, is a vertical section of the backhead connection of the actuating mechanism.

Referring in detail to the drawings, at the top of the engine boiler 1, a whistle 2 of the usual locomotive type is disposed. The whistle comprises the chime member 3 formed of an outer cylindrical shell 4, and an inner cylindrical tube 5, disposed concentrically of the outer shell, the space between the shell and the inner tube being divided into a plurality of chime chambers 6 and 7. At the lower end of the tube 5, internal screw threads 8, are cut, by means of which a valve casing 9, is attached thereto, the casing being closed at its upper end. Integrally formed on the casing 9, is the bowl member 10, and a circular outwardly extending flange 11 is formed on the lower end of the tube 5 having a diameter of such dimension as to adapt the same to fit within the top of the bowl 10 with sufficient clearance from the inner wall of the same to provide an outlet passage-way 12 for the steam when blowing the whistle.

The casing 9 is provided with ports 13, within the bowl to permit the flow of steam therethrough. The casing extends down-

wardly and its lower end is fitted into the cylinder 14 by means of the screw threads 15, the end of the casing being formed to provide a valve seat 16. A valve 17, the stem of which is slidably disposed within the casing 9, rests when in closed position, on the seat 16.

On one side of the casing 9, an outwardly projecting hollow extension 18 is formed, in which is disposed a bell crank lever 19, pivoted on a pin 20. The lower arm of the lever projects through the extension 18 in the valve casing 9 into a slot 21 formed in the stem of the valve 17. In the side of the casing 9, a stud 22 is screwed, extending into the slot 21 so as to provide a stop, preventing the valve from rotating in the casing 9 or from dropping through the casing when the lever 19 is removed. The bell crank lever 19 is operably connected to the hand control lever 23 in the cab 24 by means of the rods 25 and the lever 26.

Coming now to the features of construction novel to the present invention, the valve 17 is provided with an extension 27, on which is formed head 28. The cylinder 14 is screwed in the plate 29 of the boiler 1 of the locomotive into which it extends, the plate and cylinder being provided with screw threads 30.

A piston member 31, is disposed in the lower portion of the cylinder 14, and is provided with an upwardly and inwardly extending wall 32, providing a recess 33 into which the enlarged head 28 is introduced through a slot 34 formed in the upper part of the wall 32 before the same is assembled, whereby the valve is operably connected to the piston.

Formed in the sides of the cylinder 14, within the boiler 1, are ports 35 which permit an uninterrupted admission of steam into the cylinder 14 to exert pressure against the upper side of the piston 31, and the underside of the valve 17. The under side of the valve 17 is of an area slightly less than the area of the upper side of the piston 31. An annular groove 36 is formed in the outer wall of the piston 31, and a plurality of ports 37 formed in said piston, connect the groove with the interior of the cylinder beneath the piston.

Ports 38 are formed in the wall of the cylinder 14 and are adapted to coact with the groove 36, and ports 37 as will be hereinafter described.

6 Mounted in the rear end of the boiler 1 within the cab 24 is a backhead connection 39 (Figs. 1 and 6). The connection 39 comprises an integral casting having a passage 40 opening into the boiler 1 and which passage is in communication with outlet ports 41 and 42. 10 A pipe 43 connects the lower portion of the cylinder 14 beneath the piston 31 with the port 41, and a pipe 44 connects the port 42 with the atmosphere. An operating valve 45 of any suitable type is provided in the pipe 44 within the cab 24, to control the flow of steam through the exhaust pipe 44, the rate of flow of steam through the passage 40 is controlled by means of a regulating screw 46 provided in the connection 39.

15 In operation, the steam from the boiler 1 will pass freely through the ports 35 exerting its pressure on the underside of the valve 17, and the upper side of the piston 31. When 20 the operating valve 45 is in closed position the steam will pass through the passage 40 in the backhead connection 39, and through the pipe 43 into the lower part of the cylinder 14, exerting a balancing pressure against the 25 underside of the piston 31, so that it will exert no force on the enlarged head 28 of the valve, and the same will be held upon its seat 16 by the aforesaid pressure. Upon opening the 30 valve 45, the steam from the passage 40 will tend to exhaust itself through the pipe 44 into the atmosphere, and the pressure in the 35 lower part of the cylinder 14 will be reduced so that the piston 31 will be forced downwardly by the excessive pressure exerted on its upper side; the piston wall 32 being connected with the head 28, the latter will be pulled downwardly with the piston, opening the 40 valve and blowing the whistle. As aforesaid the regulating screw 46 will be set to 45 prevent steam from flowing from the passage 40 faster than the same can be exhausted through the pipe 44.

50 When the operating valve 45 is either wide open or entirely closed, the ports 38 are not in line with the annular groove 36 and ports 37. As soon as the valve 17 is open slightly, its tendency is to spring to wide open position, the groove 36 instantly passing the ports 38. In closing the whistle valve 17, when the 55 exhaust valve 45 has been shut off, the pressure will again build up within the lower portion of the cylinder 14 at the underside of the piston 31, and the piston will move gradually upward until the groove 36 and the ports 38 come in line with each other, whereupon a greater quantity of steam will be suddenly introduced through the groove and ports into the lower portion of the cylinder and will quickly force the piston 31 and

the valve 17 connected thereto upward into closed position.

From the foregoing description it will be apparent that the invention provides a simple operating valve, the only function of which is to open and close the exhaust passage from the backhead connection to the atmosphere. This obviates the three way valve ordinarily used to both supply and exhaust the operating fluid. No change is required by the present invention in the construction of the whistle, except the extension 27 and enlarged head 28 on the valve. 70 75

80 While a specific embodiment of the present invention has been hereinbefore described, it will be understood that all and any changes and modifications in the details of construction of the same which may prove desirable and will be apparent to those skilled in the art, are contemplated as within the spirit of 85 the present invention and the scope of the appended claims. The actuating mechanism may of course be used with any whistle of the fluid operated type, and the cylinder 14 need not necessarily be disposed within a boiler but 90 may be located in any convenient place outside of the same, and the steam or actuating fluid then being supplied thereto by pipes or other means, instead of directly from the 95 boiler.

95 It will be apparent that in a whistle where the actuating mechanism of this invention is used, the manual operating mechanism is not interfered with, but provides an additional or auxiliary means of operating the 100 whistle.

The invention claimed and desired to be secured by Letters Patent, is:—

105 1. An actuating mechanism for a steam whistle having an operating valve, comprising means for effecting an application of fluid pressure in said mechanism to hold the said valve in closed position, and means for varying the application of said fluid pressure to actuate said valve.

110 2. The combination of an actuating mechanism for a steam whistle having an operating valve, comprising means for effecting an application of fluid pressure in said mechanism to hold the valve in closed position, and means for varying the application of said fluid pressure to actuate said valve together with means for manually operating the said valve.

115 3. An actuating mechanism for a steam 120 whistle having an operating valve, comprising a fluid actuated member operably connected to said valve, means to effect an application of fluid pressure on said valve to hold the same in closed position and to effect an application of said fluid pressure on the opposite sides of said member to normally maintain the same in a balanced neutral position, and means for varying the application of said fluid pressure on one side of the said member 125 130

to actuate the same by the unbalanced pressures and operate the said valve.

4. The combination of an actuating mechanism for a steam whistle having an operating valve, said mechanism comprising a fluid actuated member operably connected to said valve, means to effect an application of fluid pressure on said valve to hold the same in closed position and to effect an application of 10 said fluid pressure on the opposite sides of said member to normally maintain the same in a balanced neutral position, and means for varying the application of said fluid pressure on one side of the said actuating member to operate the same and open and close the said valve, together with means connected with said valve to manually operate the same independently of the said actuated member.

5. An actuating mechanism for a steam 20 whistle having an operating valve, comprising a cylinder enclosing the said valve, a piston disposed within said cylinder and operably connected with said valve, means for introducing fluid pressure into said cylinder 25 so as to exert pressure against the said valve to normally hold the same in closed position and against the upper and lower sides of said piston to normally hold the same in neutral closed position, and means to vary the said 30 pressure in the lower portion of said cylinder whereby the said piston will be actuated by the unbalanced pressures on its opposite sides to operate the said valve.

6. An actuating mechanism for steam 35 whistles having an operating valve, comprising a cylinder enclosing said valve, a piston disposed within said cylinder and operably connected with said valve, the said cylinder having a port formed therein to permit the 40 introduction of fluid pressure to exert pressure against the valve to normally hold the same in closed position, and against the upper side of said piston, and said cylinder having a port formed in the lower part of same adapt- 45 ed to permit the introduction of fluid pressure to exert pressure against the underside of said piston to normally hold the same in balanced closed position, and means for varying the said pressure on the underside of said 50 piston whereby the same will be actuated by the unbalanced pressures to operate the said valve.

7. An actuating mechanism for steam 55 whistles having an operating valve, comprising a cylinder enclosing the seat end of said valve, a piston disposed within said cylinder and operably connected with said valve, the said cylinder having a port formed therein to permit the introduction of fluid pressure into 60 said cylinder to exert pressure against the valve to hold the same in closed position, and against the upper side of said piston, and said cylinder having a second port formed therein to permit the introduction of fluid pressure into 65 to exert pressure against the underside of

said piston to normally hold the same in neutral closed position, means for varying the pressure on the underside of said piston whereby the same will be actuated by the unbalanced pressures to operate the said valve, 70 and means operatively connected with the stem of the said valve adapting the same to be manually operated independently of said actuating mechanism.

8. An actuating mechanism for a locomotive whistle having an operating valve, comprising a cylinder enclosing the seat end of said valve and extending into the boiler of the locomotive, a piston disposed within said cylinder and operably connected with said valve, the said cylinder having a port formed therein within the said boiler and adapted to permit the introduction of steam from said boiler into said cylinder to exert pressure against the valve to hold the same in closed position, and against the upper side of said piston, and said cylinder having a second port formed therein in communication with the boiler and normally adapted to permit the flow of steam from the same to the lower portion of the cylinder to exert pressure against the underside of said piston and hold the same in balanced closed position, and means for exhausting the flow of steam from the boiler to the last said port to vary the pressure on the underside of said piston whereby the same will be actuated by the unbalanced pressures, 85 to operate the said valve.

9. An actuating mechanism for a locomotive whistle having an operating valve, comprising a cylinder enclosing the seat end of said valve and extending into the boiler of the locomotive, a piston disposed within said cylinder and operably connected with said valve, the said cylinder having a port formed in the same within the said boiler to permit the introduction of steam from said boiler into said cylinder to exert pressure against the valve to hold the same in closed position, and against the upper side of said piston, and said cylinder having a second port formed therein in communication with the boiler to normally permit the flow of steam from the same to the lower portion of the cylinder to exert pressure against the underside of said piston and hold the same in balanced closed position, means for exhausting the flow of steam from the boiler to the last said port to vary the pressure on the underside of said piston whereby the same will be actuated by the unbalanced pressures to operate the said valve, and means operably connected with the stem of the said whistle operating valve adapting the same to be manually controlled independent of the said piston.

10. An actuating mechanism for steam whistles having an operating valve, comprising a cylinder enclosing the seat end of said valve, a piston disposed within said cylinder and operably connected with said valve,

means to permit the introduction of fluid pressure into said cylinder to exert pressure against the valve and normally hold the same in closed position, and against the upper side of said piston, means to permit the introduction of fluid pressure to exert pressure against the underside of said piston to normally hold the same in a balanced closed position, means for varying the pressure on the underside of said piston whereby the same will be actuated by the unbalanced pressures to make reciprocating strokes to operate the said valve, and means to permit the sudden introduction of a relatively large quantity of fluid pressure during the closing stroke of said piston to quickly return the same to closed position.

11. An actuating mechanism for steam whistles having an operating valve, comprising a cylinder enclosing the said valve, a piston disposed within said cylinder and operably connected with said valve, the said cylinder having a port formed therein to permit the introduction of fluid pressure into the same to exert pressure against the valve and normally hold the same in closed position, and against the upper side of said piston, and said cylinder having a second port formed therein to permit the introduction of fluid pressure to exert pressure against the underside of said piston to normally hold the same in a balanced closed position, and means for varying the pressure on the underside of said piston whereby the same will be actuated by the unbalanced pressures to make reciprocating strokes to operate the said valve, the said piston and cylinder having coacting ports formed in their respective adjacent sides normally out of line with each other, and adapted when brought into line during the closing stroke of said piston to permit the sudden introduction of a relatively large quantity of fluid to quickly actuate said piston in its said closing stroke.

12. An actuating mechanism for a locomotive whistle having an operating valve, comprising a cylinder enclosing the said valve and extending into the boiler of the locomotive, a piston disposed within said cylinder and operably connected with said valve, the said cylinder having a port formed therein within the said boiler to permit the introduction of steam from same into the cylinder to exert pressure against the valve and normally hold the same in closed position, and against the upper side of said piston, and said cylinder having a second port formed therein within said boiler and in communication with the same, to permit the introduction of steam therefrom to the lower part of the cylinder to exert pressure against the underside of said piston to normally hold the same in a balanced closed position, and means for varying the pressure on the underside of said piston by exhausting

the flow of steam from the boiler to the lower part of the cylinder whereby the piston will be actuated by the unbalanced pressures to make reciprocating strokes to operate the said valve, the said piston and cylinder having coacting ports formed in their respective adjacent walls within the boiler and normally out of line with each other, and adapted to be brought into line during the closing stroke of said piston to permit the sudden introduction of a relatively large quantity of steam from said boiler to quickly actuate said piston in its said closing stroke.

13. A fluid actuating mechanism for operating a locomotive whistle having an operating valve, comprising a fluid actuated member operably connected to said valve, a source of fluid pressure, means for effecting the constant application of the fluid pressure from said source on the underside of said valve to normally hold the same in closed position and on the upper side of said actuating member, connecting elements adapted to deliver fluid pressure from said source to the underside of said actuated member to normally maintain the same in a balanced closed position, and means associated with said connecting elements adapted to exhaust the fluid pressure flowing therethrough from said source, to the atmosphere, whereby the pressure applied to the underside of the said piston may be varied and the said piston actuated by the consequent unbalanced pressure on its opposite sides, to operate the said valve.

14. The combination of a fluid actuating mechanism for operating a locomotive whistle having an operating valve, said mechanism comprising a fluid actuated member operably connected to said valve, a source of fluid pressure, means for effecting the constant application of the fluid pressure from said source on the underside of said valve to normally hold the same in closed position and on the upper side of said actuating member, connecting elements adapted to deliver fluid pressure from said source to the underside of said actuated member to normally maintain the same in a balanced closed position, means associated with said connecting elements adapted to exhaust the fluid pressure flowing therethrough from said source, to the atmosphere, whereby the pressure applied to the underside of the said piston may be varied so that the piston will be actuated by the consequent unbalanced pressures on its opposite sides, to operate the said valve, and connections to said valve adapted to manually operate the same independently of the said actuating mechanism.

15. A fluid actuated mechanism for operating a steam whistle having an operating valve, comprising a cylinder mounted on said whistle surrounding the said valve, a piston disposed in said cylinder and operably con-

- connected with said valve, a source of fluid pressure, said cylinder having ports formed therein to admit the said fluid pressure into the same to exert pressure against the said valve to normally hold the same in closed position and against the upper side of said piston, a connecting element having a passageway in communication with said source of fluid pressure, connecting means between said element and said cylinder whereby the said fluid pressure will be normally delivered from said passageway to the cylinder at the underside of the said piston to normally hold same in a balanced closed position, and an exhaust connection for said element having a valve associated therewith whereby the fluid pressure from the said passageway may be exhausted into the atmosphere to vary the pressure at the underside of said piston and actuate the same by the consequent pressures on its opposite sides to operate the said whistle valve.
16. A fluid actuated mechanism for operating a locomotive whistle having an operating valve, comprising a cylinder mounted on said whistle surrounding the seat end of said valve, and extending into the boiler of the locomotive, a piston disposed in said cylinder and operably connected with said valve, a source of fluid pressure, ports formed in the said cylinder within said boiler to admit the steam from the same into the cylinder to exert pressure against the said valve to normally hold the same in closed position and to exert pressure against the upper side of said piston, a connecting element mounted on said boiler having a passageway communicating with the interior of the same, connecting means between said element and said cylinder whereby the said steam will be normally delivered from the said passageway to the cylinder at the underside of the said piston to hold same in a balanced closed position, and an exhaust connection for said element, having a control valve associated therewith whereby the steam from the said passageway may be exhausted into the atmosphere to vary the pressure at the underside of said piston and actuate the same by the consequent pressures on its opposite sides to operate the said whistle valve.
17. A fluid actuated mechanism for operating a locomotive whistle having an operating valve, comprising a cylinder mounted on said whistle surrounding the seat end of said valve, and extending into the boiler of the locomotive, a piston disposed in said cylinder and operably connected with said valve, a source of fluid pressure, said cylinder having ports formed therein within said boiler to admit steam from the boiler into the cylinder to exert pressure against the said valve to normally hold the same in closed position and against the upper side of said piston, a connecting element mounted on said
- boiler having a passageway communicating with the interior of the same, connecting means between said element and said cylinder whereby the said steam will be normally delivered from the said passageway to the cylinder at the underside of the said piston to hold same in a balanced closed position, an exhaust connection for said element having a control valve associated therewith whereby the steam from the said passageway may be exhausted into the atmosphere to vary the pressure at the underside of said piston and actuate the same by the consequent pressures on its opposite sides to operate the said whistle valve, and means formed in the said cylinder and valve to permit the sudden introduction of a relatively large quantity of pressure when the said piston is operating to close the valve, to quickly return the same to its closed position.
18. A fluid actuated mechanism for operating a locomotive whistle having an operating valve, comprising a cylinder mounted on said whistle surrounding the seat end of said valve, and extending into the boiler of the locomotive, a piston disposed in said cylinder and operably connected with said valve, said cylinder having ports formed therein within said boiler to admit steam from the said boiler into the cylinder to exert pressure against the said valve to normally hold the same in closed position and against the upper side of said piston, a connecting element mounted on said boiler having a passageway communicating with the interior of the same, connecting means between said element and said cylinder whereby the said steam will be normally delivered from the said passageway to the cylinder at the underside of the said piston to hold same in a balanced closed position, an exhaust connection for said element having a control valve associated therewith, whereby the steam from the said passageway may be exhausted into the atmosphere to vary the pressure at the underside of said piston and actuate the same by the consequent pressures on its opposite sides to operate the said whistle valve, and means connecting with said valve to manually operate the same independently of the said actuating mechanism.
19. A fluid actuated mechanism for operating a locomotive whistle having an operating valve, comprising a cylinder mounted on said whistle surrounding the seat end of said valve, and extending into the boiler of the locomotive, a piston disposed in said cylinder and operably connected with said valve, said cylinder having ports formed therein within said boiler to admit the steam from the said boiler into the cylinder to exert pressure against the said valve to normally hold the same in closed position and against the upper side of said piston, a connecting element mounted on said boiler having a pas-

sageway communicating with the interior of the same, connecting means between said element and said cylinder whereby the said steam will be normally delivered from the 5 said passageway to the cylinder at the underside of the said piston to hold same in a balanced closed position, an exhaust connection for said element having a control valve associated therewith whereby the steam from 10 the said passageway may be exhausted into the atmosphere to vary the pressure at the underside of said piston and actuate the same by the consequent pressures on its opposite sides to operate the said whistle valve, means 15 formed in the said cylinder and valve to permit the sudden introduction of a relatively large quantity of pressure when the said piston is operating to close the valve, to quickly return the same to its closed position, and 20 means operably connected with the stem of the said whistle valve adapting the same to be manually operated independently of the said piston.

20. The combination of a locomotive whistle; a valve for supplying steam for operating the whistle; valve opening and closing means including three faces movable in unison with the valve and in the same direction by the application of fluid under pressure; a 25 first face adapted to be acted upon by the fluid in a valve closing direction, a second face of larger area than the first face adapted to be acted upon by the fluid in a valve opening direction, and a third face adapted to 30 be acted upon by the fluid in a valve closing direction and of sufficient area to ensure normal closing of the valve; and means for reducing the pressure on said third face to effect the opening of the valve.

21. The combination of a locomotive whistle; a valve for supplying steam, for operating the whistle; valve opening and closing means including three faces movable in unison with the valve and in the same direction by the application of fluid under pressure thereto, one of said faces adapted to be acted upon by the fluid in a valve closing direction, another of said faces adapted to be 35 acted upon by the fluid in a valve opening direction, and the remaining said face adapted to be acted upon by the fluid in a valve closing direction; means for applying fluid under pressure simultaneously to said three faces; and means for varying the pressure of the fluid against at least one of said faces for operating said valve, said faces being of suitable relative areas to insure the maintenance of the valve closed when a fluid of uniform pressure is applied to each of the 40 faces and for insuring the operation of said valve with said variation of the pressure.

22. An actuating mechanism for a steam whistle having an operating valve, comprising a plurality of faces of varied areas; means 45 for applying fluid under pressure to said

faces; and means for varying the pressure against one of said faces, the areas of said faces being of such relative proportions as to effect the closing of the said valve when the fluid under pressure is applied uniformly 70 to said faces and to effect the operation of said valve upon the said variance of pressure.
